(54) **PRINTING PRESS, POWER**

(76) Inventor: **Isaac Adams**

Isaac Adams of Boston Massachusetts
Letters Patent. Received April 30th 1858.

The Schedule referred to in these Letters Patent and making part of the same containing a description of the words of the said Isaac Adams, himself of his improvement in the Printing machine called a "Plan Printing Press."

To all persons to whom these presents shall come, Isaac Adams of the City of Boston in the County of Suffolk and State of Massachusetts, merchant, Greeting. Be it known that I the said Isaac Adams, have invented, constructed, made and applied to use, sundry new and useful improvements in a printing machine called a "Plan Printing Press," Specified in the words following viz. The frame of the machine is 9 feet long 3 feet wide and 3 feet 2 inches high. The top rails which run lengthwise of the frame, are 9 inches deep and 3 inches thick. The two posts, at one end of the frame are one foot wide 3 inches thick and as high as the top of the ^{top} rails. The ends of which are tenoned into the edges of the posts. The posts or legs, at the other end of the frame are 5 inches wide, and 3 inches thick and are tenoned into the under edges of the rails 4 inches from their ends. The two posts on each side are connected to each other lengthwise of the frame by rails, the dimensions ^{of which} are the same in width & thickness as the small posts. These rails are tenoned into the posts 7 inches from their bottom ends. The two sides of the frame are connected together by 3 cross bars between the two large posts and 2 at the other end of the frame. The lower bar between the two large posts is 4 inches deep and one foot wide and is tenoned into the posts 3 inches from their bottom ends. The 2nd bar is of the same dimensions as the bottom one and is tenoned into the posts 16 $\frac{1}{2}$ inches above it. The top bar which is 8 inches deep is tenoned into the posts 2 inches below the top of the frame. The cross bars at the other end of the frame are 4 inches square, and the bottom one is tenoned into the legs, 7 inches from their bottom ends, and the top one into the top rails, 5 inches below the top of the frame. The bed which the frame is laid on is a plate of cast iron having a number of bars running lengthwise and cross wise, on its upper side to support it down. This is when the impression is iron. The

extended by act of Congress until the second day of March 1864 (see vol 1/288)

bed, is $2\frac{1}{2}$ feet long and 2 feet wide, and is placed in a horizontal position between the 2 top rails 4 feet from the end of the frame, with the large posts and is kept steady in rising and falling (which it is made to do every impression) by a guide at each end of the bed which runs in grooves on the inside of the top rails. The guides are small rods on pieces of cast iron which are fastened to the ends of the bed and run down far enough below the bed to rest on the lower rails of the frame when the top side of the bed is $5\frac{1}{2}$ inches below the top of the frame, a bar of cast iron is then placed across the frame and directly under the center of the bed to sustain the impression. This bar is 9 inches deep in the middle 6 inches deep at the ends, and 2 inches thick and is made in a crooked form, so that when the ends come up against the under side of the lower rail, a straight place in the middle and on the top edge of the bar will be as low as the bottom ends of the posts (when the machine is set up there must be a place cut in the floor to receive this bar) There is also a hole thro' each end of this bar which receives bolts 2 inches in diameter, that pass up thro' projections on the lower ends of the before named guides close to the sides of the frame and 3 inches above its top. The bolts have heads on their bottom ends, and nuts on their top ends which go on the bolts with a square threaded screw. The plattin is like the bed except that it is 4 inches narrower and it makes shorter, and has a projection at each corner by which the plattin is suspended on rods placed on the top rail to slide it off when the form is put on the bed and other projections on the ends strong enough to sustain the impression, with slots or apertures in their sides (next to the end of the frame which has the large posts) to receive the bolts. The bed is raised and the impression given by means of irons called toggle joints which are operated by a crank and pitman. The toggle joints are applied between the bed and the iron cross bar before named, and the crank is hung to the 2 iron cross bars in the end of the frame. The pitman is connected to the crank with a flat staple or slat of iron which goes round one side of the neck of the crank and receives the end of the pitman between the two ends where it is held by a pin passed through the ends of the staple and the end of the pitman. The

round the end of the pitman and the neck of the crank there is a block, if iron which is, so formed as, to fit on to the neck of the crank and on to the end of the pitman which is, also rounded so as to form a joint on the end of the pitman corresponding with the pin which holds them together in order that the other end of the pitman may be moved up and down which it is, constantly doing when in operation.

On account of its being necessary to raise and lower flushed with one half of the revolution of the crank. it is, made eccentric 8 inches, which gives 16 inches motion to the pitman in the direction of the length of the frame, this is nearly twice as much as, is necessary to move the toggle joint, therefore 10 inches of the pitman is, made one inch narrower than the other part, which leaves a projection on its under edge, so that when the pitman has received one half of its motion towards the bed, the projection strikes an apparatus (hereinafter described) and carries the toggle joint up until the 2. bars, which compose them become nearly perpendicular, then the pitman is, drawn back by the crank and the rest of the bed springs, the toggle joint, and the 2. bars which operate against each other - follow the pitman until the bed falls to its place of rest when the projection on the pitman leaves its bearing until the crank has, passed the other half of its revolution.

The narrow part of the pitman sliding thro a slot made on the upper lever for that purpose, and over a pin which goes through the middle joint. Here it may be observed that the toggle joints are least powerful when they first begin to operate and ^{that} the pitman is, moving fastest towards them at that time, and fastest from them when they stop.

Undoubtedly (if there was nothing to prevent it) the pitman would strike so hard and the bed would stop so sudden that it would cause the machine to shake and make considerable noise. For these reasons I have put the apparatus before named (which I shall call the "dead-man lever") on the lower lever of the toggle joint, for the pitman to strike against. The name of the lever signifies its property or nature, for it is almost infinitely powerful when it begins to operate and decreases to nothing. It is made of inches long 2 inches wide, one inch thick.

at its lower end, and a half an inch thick at the top end which has a rounded projection across it for the pitman to strike against; it is made curving about one inch with its whole length, and put on the lower lever of the togle joints so that its top end will be level with the pin in the middle joint and the bottom end between the lower togle and a bar that is placed across the same for the lever to rest on, that side of the lever being next to the togle) which forms the outline of a curve. The bar is kept in its place by 2 thin plates of iron one projecting out from the togle each side of the lever, in these projections near to the bottom end of the lever there are slots in which a pin moves, that is, put through the end of the lever. The slots are long enough to permit the end of the lever to have its progression and this rule ends one half of an inch lower than the ends, next to the togle joints) so that when the bottom end of the lever is thrown out the slot will cause it to slip downward on the togle joints, when the pitman strikes this lever it causes it forward, the lower end remaining on its bearing which serves for the fulcrum of the lever, and the togle joints are forced up gradually the resisting power resulting from the fulcrum until the lever is brought to bear upon its top end when it is carried along with the togle joints until the impression is given when the togle joints return the lower end of the lever strikes its bearing first and it operates with a progressive force, in raising the heft of the bed until it comes to its place of rest. In order to prevent the machine from giving an impression in case of necessity there is a bar of iron placed across the frame on the two lower rails, and under the pitman, with a cradle or lever attached to each end of it which are hung to the sides of the tail, so that the person at either end of the machine who lays on the paper may push the end of one of the levers down with the foot which will raise the pitman high enough to clear the projection and permit it to pass thro' the slot in the upper lever of the togle joints without moving them. The weight is distributed by a set of rollers on each side of the bed, with an interval between each set. The under composition rollers are placed so that their centers will be $1\frac{1}{2}$ inches from the edges of the bed & $3\frac{1}{2}$ below

its upper side, a wooden Roller six inches shorter than the composition Rollers is then placed against each of the bottom Rollers on the sides next to the bed, which serve to equalize the ink by a reciprocating movement of six inches, inclusive. Two other composition Rollers of the same length of the bottom ones, are then placed on each of the bottom Rollers, so that their top sides will be level with the type on the bed when it is in its lowest situation. These composition Rollers are supported by pivots in their ends, which are in bases fastened to the inside of the frames. The fountains are iron troughs, which have an iron Roller lying lengthwise in the middle of each of them. The Rollers are placed so that the top sides of them are one half of an inch higher than the sides of the troughs. In order to gauge the quantity of ink drawn out of the fountains on the Rollers, there is a scraper to each fountain, made of a thin plate of iron and fastened with screws to one side of the trough, one edge of which is well fitted to the sides of the rollers. The holes through which the screws are put through, to hold the scraper on to the sides of the troughs, are made a little oblong or square so that the scrapers may be moved nearer to or farther from the rollers in order to let out more or less ink. The fountains are placed on a sliding frame near to, and parallel with the bottom composition Rollers. The fountain Rollers being level with the under side of the composition Rollers. The frame which supports the fountains is formed of 4 bars, 2 of which run across the front frame and are supported at their ends by lugs, secured to the top rails. The other 2 bars, pass under the bed lengthwise of the frame and connect the 2 frames to each other. A reciprocating movement is given to this frame and consequently to the fountains by means of an eccentric gear formed on the top side of a horizontal plate of iron on the shaft of the crank which operates on a projection on the under side of the flat Rod that is attached to the frame and held steady in a box fastened to the under side of the middle cross bar. The gear is so formed that it moves the fountains one inch in going one way of its revolution where it permits them to stand still until it has passed 5 halfths more of its revolution, when the fountains are drawn back in the same time they were moved forward. The fountain Rollers are moved by pulleys which

are attached to the side of the top rails, and operate on sash wheels on the ends of the rollers, so that they are turned a little every reciprocation of the frame and fountain. The ink is taken from the fountain and communicated to the composition Rollers by small wooden Rollers which lie on the top of the fountain Rollers where they are held by pivots in their ends which run in holes made in the ends of the springs that are fastened to the sliding frame and run up in a curved form over the fountain. When either of the fountains are moved towards the distributing Roller, the small wooden Roller is raised clear from the fountain roller by means of studs projecting out from the sides of the top rails, and under the springs, so that when the fountains are moved, the springs slide up on the studs and raise the roller which is, at the same time, carried against the composition roller where it leaves a portion of the ink. The reciprocating Rollers are attached to two bars, the ends of which slide in boxes attached to the under edges of the top rails. These bars are connected to each other by 2 other bars, one of which runs lengthwise of the machine on each side of the top joints.

The reciprocating movement is given to these rollers by means of a lever one end of which is hung to the under side and in the middle of one of the connecting bars last above named. The other end of the lever has a projection on it which runs in a groove in the joint of a bar made around the shaft of the crank, in the top side of the before-named horizontal plate. There are still 2 other composition Rollers which distribute the ink over the type by being moved over the bed from one set of rollers to the other, from which they receive a sufficient quantity of ink for every impression. These Rollers are hung in the middle of a frame 5 feet long which runs in rabbits made in the inside corners of the top edges of the top rails of the machine. This frame is made of 2 side pieces 8/8 inch square, and 2 end pieces 1 1/2 inch thick and 3 wide, and it is kept from rising out of its place by thin plates of iron fastened on to the top rails so as to project a little over its side pieces. The Rollers are hung by pivots in their ends which run in boxes fastened to the side pieces with screws. The holes which the screws are put thro are made oblong especially so that the Rollers may be adjusted to the type by raising

or lowering the bearings. There are 2 friskets hung on this frame, one on each side of the rollers, so that when the rollers are on one side of the bed, one of the friskets will be under the platen, and when they are carried over the type to the other side that frisket is carried out, and the other one drawn in, one edge of the friskets is hung by pivots, which are let into the top of the side pieces, near to the end pieces, and are kept in their places by buttons, over the pivots. The other edges of the friskets are suspended by a spring at each corner which rests on the pieces forming the bearings for the rollers. It is found by experience that the sheet would sometimes break at the point holes, on account of its being left loose in the frisket before it was clear from the type; in order to prevent this I have put springs on the under sides of the friskets which keeps them up snug to the platen until the sheet is entirely clear from the type which effectively prevents the sheet from breaking. The edges of the friskets next to the rollers are about 1 inch lower than the outer edges, which is to prevent the air from blowing the sheet from the points when it is moved in quick. The friskets with the rollers and frame to which they are hung are operated by a crank motion on the end of a shaft which stands on the end of the shaft of the main belt that gives the impression. The top end of a bar forms a step for the lower end of the main shaft. In order to give a practical motion to this shaft an iron bar 18 inches long 3 inches deep and one inch thick is put thro it, near to its lower end, and hung at its center on a pin which is put thro the shaft.

The top end of the lower crank shaft has an arm round with a projection on its upper side which strikes the bar ^{near} one end and carries it around one half of a revolution which moves the rollers over the bed by means of the crank and pulley on its top end. That end of the bar is then raised by an inclined plane, on the middle cross bar of that end of the frame so as to clear the projection on the arm. The friskets with the rollers and frame then stop until the impression ^{is given} when the arm strikes the other end of the bar and carries the rollers over the form again, and so on in rotation. When I first projected this machine, I calculated to put the paper directly on to the friskets, but I found in that case

there would be a loss of nearly one half of the time in putting on the sheets; to prevent this loss of time I have made 2 fly frames which correspond in size to the friskets and covered them with a coarse net work one of which is hung at each end of the machine on pivots, so that when either of the frames are out one of the frames may be turned down on to it where it leaves the sheet previously pinned on the fly frame. These frames are made with 2 cross bars, one passing across the middle of the frame each way. At proper distances from the edges of the frames for the points there are apertures or niches cut in these bars which receive small slides 3 inches long with points on them. The slides are made in a dovetail form so that by turning them in against them, from the back sides of the frames they may be kept in their places. There are also other points on rods which are fastened to the friskets with screws. The hole which the screws go through being made oblong or opposite of the rods so that the points on the friskets may be adjusted in a line with the points on the frames. The fly frames are operated by means of a cog wheel on that pivot of each frame which is on the opposite side from where the persons stand to put on the paper. Each of these wheels is operated by 2 segments of different sized cog wheels, which are connected together. The smallest one of which goes into racks fastened to slide rails which run along the sides of the machine and are connected to each other by cross bars, one of which is near to the crank, and the other near to the other end of the machine. The edge of the bar near the crank is so formed that a friction roller, which is attached to the crank just above the pitman, shall strike it, and move the slide rails far enough to turn down the fly frames and so that they may be drawn back by a weight as the friction roller moves along on the edge of the cross bar. The weight is attached to the cross bar which connects the other ends of the slide rails. Here it must be observed that if the large segment, goes directly into the cog wheel on the fly frame at the opposite end of the machine from the crank it would turn it the wrong way. Therefore an intermediate wheel is put on to the top rail so as to gear into the wheel on the fly frame, and the large segment. In order to prevent both of the

guration are not to be considered a rule in all cases but the machine must be proportioned to the work that is to be done with it.

The above is a Plain Specification of the whole machine, and those parts which I claim as my invention are designated as followz Viz. The combination of Stationary fly frames, with points for getting Register by, on them with Printing Presses. The object of these fly frames is to enable the person who lays on the paper, to print one sheet while the sheet previously put on, is receiving the impression and by that means save the time which would be lost in waiting for the sheet to come out.

Furthermore I claim the apparatus described in the foregoing Specification for giving a periodical movement to the rollers & friskets, that is, I do not claim the parts separately but merely that combination of parts to produce the effect as set forth in the Specification. And furthermore I claim as my invention the application of the declination Lever set forth and described in the foregoing Specification. In testimony that the above is a true Specification of my said improvements as above described I have here to set my hand and seal the 14th day of April in the year of Christ one Thousand Eight hundred and thirty
